UNITED STATES PATENT OFFICE.

ALBERT WEICKMAN, OF HARRISON, AND CHANCY S. OLMSTED, OF MOUNT VERNON,
NEW YORK.

RESILIENT SUPPORT FOR CUSHION SEATS.

Application filed December 22, 1926. Serial No. 156,491.

This invention relates to resilient supports for cushion seats, and has particular reference to a resilient support for cushioned vehicle seats, the same being in the nature of an improvement upon prior United States Letters Patents Nos. 1,027,949 and 1,584,577, granted, respectively, on May 28, 1912, and May 11, 1926.

In constructing supports of this character especially for vehicle seats, it has been noted where the seat is of a width to accommodate more than one person, the employment of a single resiliently mounted frame is of a disadvantage in view of the fact that where one person sits on one side of the seat or where persons of extremely different weights sit upon opposite sides of the seat, the single supporting frame has a tendency to become canted rendering the seat uncomfortable, straining the structure, and generally detracting from the efficiency thereof.

In order to overcome the above-recited objections and to materially add to the general efficiency of the structure, the present invention comprehends a resilient support for cushion seats which includes a stationary frame and a plurality of independently movable resiliently mounted cushion supporting elements which serve to closely conform to localized weights imposed thereon, thereby rendering the seat more comfortable to the users.

Other objects reside in the features of simplicity, rigidity and strength of construction and the economy with which the same may be produced.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a plan view of the seat support; Fig. 2 is a longitudinal sectional view therethrough taken approximately on the line indicated at 2—2 in Fig. 1;

Fig. 3 is a transverse sectional view taken

approximately on the line indicated at 3—3 in Fig. 1;

Fig. 4 is a fragmentary sectional view taken approximately on the line 4—4 of Fig. 3;

Fig. 5 is a fragmentary sectional view taken approximately on the line 5—5 of Fig. 3.

Referring to the drawings by characters of reference, the seat support includes substantially rectangular upper and lower frames 10 and 11, which are connected by vertical or upright corner and intermediate members 12 and 13. Adjacent the upper front portion of the framework a transverse bearing rod 14 is mounted, to which is pivoted in longitudinally spaced relation, elements in the nature of flexible resilient straps 15, which are preferably constructed of sheet metal bent at a point substantially intermediate the ends to provide a knuckle or sleeve 16 embracing the bearing rod 14. The remaining portions or leaves are bolted, riveted, or otherwise secured together at 17, with the free rear terminals 18 and 19 slightly offset to receive and clamp therebetween a continuous flexible transverse strip 20 of leather or other suitable material which allows for a limited relative independent vertical movement of the free rear ends of the elements 15. The extremities of the terminals 18 of each element 15, are turned up as at 21, and are apertured to receive the lower ends or convolutions 22 of coiled contractile springs 23, the upper ends or convolutions 24 of which are suitably anchored to the upper frame member 10, whereby the rear free ends of the elements 15 are normally supported by the springs 23 and tensioned against downward movement. The elements 15 are normally disposed at a rearward and downward inclination and are adapted to receive thereupon a cushion seat A. In order to prevent rearward gravitation of the seat A, the upper leaf of each element 15 adjacent its rear end, is formed with an upwardly offset portion 25 which is preferably formed integral therewith to provide an abutment or stop against which the rear end B of the cushion seat abuts. The forward end C of the cushion seat A is adapted to directly rest upon the upper frame member 10, and a depending flap or apron D is carried by the for-

ward end C to overlie and conceal the stationary frame of the support. In order to space and prevent lateral shifting movement of the fulcrumed forward ends of the elements or straps 15, the upper frame 10 may have bolted or otherwise secured thereto spacing devices 26 which also serve to support the bearing rod 14.

In use, it is obvious that a weight imposed upon the cushion seat A will effect downward movement only of the number of elements or straps 15 over which the weight is imposed with only a slight movement of the adjacent elements 15 on opposite sides by the flexible connecting strip 20. The elements 15 in addition to moving bodily down under the weight and absorbing the shocks and jars incident to travel over the road, are also capable of a slight flexing or bowing to augment the function of the springs 23.

What is claimed is:

1. A resilient support for cushion seats, including a stationary frame, a plurality of independently relatively movable cushion-supporting elements resiliently mounted in the frame at one of their ends, means for tensioning the same against downward movement at their opposite ends and for normally retaining said ends elevated, and a flexible connection between the latter ends for limiting the relative movement between the elements.

2. A resilient support for cushion seats, including a stationary frame, a plurality of resilient cushion-supporting elements, means for independently fulcruming the forward

ends of the elements to the upward forward portion of the frame, contractile means of connection between the rear ends and the upper rear portion of the supporting frame for tensioning the same against downward movement and normally retaining the same elevated, said elements consisting of a length of resilient material bent at a point substantially intermediate the ends to provide a sleeve, the remaining portions constituting leaves, securing means attaching the leaves together, and a flexible connecting means between the rear ends of the elements to permit of relative limited independent movement.

3. A resilient support for cushion seats, including a stationary frame, a plurality of resilient cushion-supporting elements, means for independently fulcruming the forward ends of the elements to the upward forward portion of the frame, contractile means of connection between the rear ends and the upper rear portion of the supporting frame for tensioning the same against downward movement and normally retaining the same elevated, said elements consisting of a length of resilient material bent at a point substantially intermediate the ends to provide a sleeve, the remaining portions constituting leaves, securing means attaching the leaves together, and a flexible connecting means between the rear ends of the elements to permit of relative limited independent movement, the rear ends of the leaves having clamping engagement therewith.

ALBERT WEICKMAN.
